UNITED STATES PATENT OFFICE.

LEONARD H. WHEELER, OF CHICAGO, ILLINOIS, ASSIGNOR TO STEWART-WARNER SPEEDOMETER CORPORATION, OF CHICAGO, ILLINOIS, A CORPORATION OF VIRGINIA.

SHOCK ABSORBER.

Application filed April 7, 1923. Serial No. 630,437. Renewed May 31, 1927.

The purpose of this invention is to provide an improved construction in a rebound check for spring vehicles of the type commonly called "snubbers." It consists of the 5 elements and features of construction shown and described as indicated in the claims.

In the drawings:—

Figure 1 is a side elevation of a construction embodying this invention, shown 10 mounted in connection with the chassis and axle of the vehicle to be served thereby.

Figure 2 is an axial section of the device, as at the line, 2—2, on Figure 1.

Figure 3 is a section at the line, 3—3, on 15 Figure 1.

Figures 4 and 5 are sections at the line, 4—5 on Figure 2, looking in opposite directions, as indicated by the arrows, 4, 5, respectively, on said Figure 2.

Figure 6 is a detail view of the fastening 20 of the cable employed as a flexible connector, to the spring take-up pulley.

Figure 7 is an edge view of the fixed drum and the take-up pulley at the side at which 25 the cable runs from the pulley to the drum.

Figure 8 is a section at the line, 8—8, on Figure 7.

In the construction shown in the drawings, "A" represents a side bar of the chassis 30 of vehicle equipped with this invention; "B" the fixed axle upon which the vehicle spring is mounted for reaction between the vehicle body and the axle. 1, is a fixed drum which is mounted upon the frame bar, "A", 35 as hereinafter more particularly described. 2, is a flexible connector from the rebound check device mounted on the frame, to the axle, being in the form of a cable wound preferably more than once about the drum, 1, which is provided with a spiral groove, 1^a, for seating the cable windings. 3 is a 40 drum or pulley, which is mounted for rotation upon a stud axle, 4, of the drum, 1, and connected therewith by coil spring, 5, the inner coil of which is made fast to a sleeve, 6, which in operation of the device is rigid with the stud axle, as hereinafter more particularly explained, and whose outer coil is made fast to the inner side of the peripheral flange, 3^a, of the spring drum or take-up pul-

ley, 3. The cable connector, 2, is attached by clips, 7, 7, to the periphery of the take-up pulley, 3, and runs from its attachment in a groove, 3^b, formed for seating the cable on the periphery of the pulley and from said 55 groove into the adjacent groove, 1^a, of the drum, 1, from the opposite end of which groove, 1^a, it runs down to its attachment by means of bracket, 8, or any other convenient means, to the axle "B."

The mode of operation of the device, as thus far described, will be understood to be that, in the original mounting, the connector cable, 2, makes nearly a full turn around the take-up pulley, and nearly three 60 turns in the spiral groove, 1^a, around the fixed drum, and is pulled down, tensioning the spring, 5, to the desired degree determined by experience in view of the load on the vehicle springs, and is then clamped to 65 the bracket, 8. When the vehicle body is depressed toward the axle by the jolting of the load when the vehicle is passing over irregularities in the track, the cable is slackened in the spiral groove of the fixed drum, and the take-up pulley, 3, under the stress of the spring, 5, takes up this slack, winding the cable in the groove of the pulley, causing it to slip in the spiral groove of the drum; and upon the rebound, the cable being 70 thus held snugly in the spiral groove, operates by friction therein to check the rebound, which can occur only by the slipping of the cable in the grooves and unwinding from the pulley, which is thereby rotated in 75 direction to tighten the spring, 5. The operation, as thus described, will be recognized as in accordance with the familiar action of 80 rebound checks of the snubber type.

The present invention is concerned with 90 details of construction, particularly with respect to the means for mounting the fixed friction drum on the frame, and means for tensioning the spring, 5, and the expedient for transferring the cable winding from the 95 single groove of the pulley to the spiral groove of the drum, and vice versa, in the rotation of the pulley for tightening the spring and its reversal for taking up the slack of the cable.

For securing the drum to the vehicle frame bar, "A", there is provided a mounting device, 10, which consists of a disk, 10^a, having a central bolt aperture and an annular serrated area, 10^b, around the bolt aperture at one side. This disk has a radial arm, 10^c, which has a projection, 10^d, extending laterally away from the side of the disk which has the serrated area mentioned. The drum, 1, has its web 1^a, centrally apertured for the stud axle, 4, which also serves as about to be described, as a means for clamping the drum to the frame; and said web has around the stud axle bolt aperture an annular serrated area, 1^b, corresponding to and adapted to cooperate with the serrated area, 10^b, of the mounting member, 10. The stud axle, 4, is in the form of a bolt, adapted to be inserted through the bolt hole, a, provided in the vehicle frame bar, "A," having its head, 4^a, at the inner side of the frame bar. The bolt extends through the central bolt aperture of the disk, 10^a, and is threaded at 4^d for screwing into the central aperture of the web, 1^a, of the drum, 1, which is interiorly threaded for that purpose.

The stud axle bolt, 4, is reduced in diameter as to the portion of its length beyond the web, 1^a, of the drum, forming a shoulder, 4^e, for stopping endwise the sleeve, 6, hereinabove mentioned. The sleeve, 6, is assembled with the pulley, 3, and spring, 5, by first securing the inner coil of the spring to the sleeve, then applying the pulley onto the inner end of the sleeve, the pulley having an annular flange, 3^a, at its inner circumference for seating rotatably on the sleeve. The outer coil of the spring is then secured to the outer flange, 3^a, of the pulley, and the entire assemblage is introduced onto the reduced portion, 4^f, of the stud axle bolt, 4. A casing, 12, is provided for enclosing the drum, cable, pulley and spring, said casing having a central aperture for fitting rotatably on the sleeve, 6, outside the spring, 5. The end of the sleeve which projects a short distance beyond the casing is squared, as seen at 6^b, to receive a spring disk, 13, having a square aperture at the center to fit the squared end of the sleeve, and, having at its periphery, spring fingers, 13^a, for bearing on the casing to hold it snugly in position with the edge of its peripheral flange, 13^b, stopped against a marginal peripheral flange, 1^c, provided at the opposite or inner side of the drum, 1. The end of the stud axle bolt is threaded to receive a nut, 15, which, being screwed on to the stud axle bolt, retains the disk spring, 13, on the squared end of the sleeve and clamps the sleeve against the shoulder, 4^e, of the stud axle bolt, rendering the sleeve rigid with the stud bolt.

The length of the radial arm of the mounting member, 10, is designed to be con-

siderably more than the distance of the bolt hole in the frame bar, "A," to the outer edge or corner of a frame bar of minimum dimensions, and long enough so that the lateral projection, 10^d, of said radial arm may engage under the corner of the frame bar of maximum dimensions.

It will be understood that the purpose of thus dimensioning the mounting member is that it may serve for mounting the snubber by means of the stud axle bolt in the bolt hole which is customarily provided in the side bars of automobile chassis of varying dimensions, the stress of the connector cable tending to rotate the entire structure on the securing bolt and stud axle, operating to swing the radial arm of the mounting member about the bolt until the projection, 10^d, is stopped against the under side of the frame bar, the swing being more or less as the dimension of the frame bar is less or more, but the security of the fastening being as complete in one case as in the other.

The purpose of the squared connection of the spring disk, 13, to the sleeve, 6, is to adapt the spring disk to serve as a handle for rotating the sleeve to initially tension the spring, 5, the nut, 15, being, of course, slackened for the purpose and tightened to hold the sleeve, and thereby the inner coil of the spring, securely as adjusted.

It will be noted from Figure 7 that the coil of the cable lying in the groove, 3^b, of the pulley, 3, runs normally and readily therefrom into the entering end of the spiral groove, 1^a, of the drum when the cable is being pulled from the drum, when the vehicle is rebounding after a depression; and that the cable will with equal facility be drawn back into the groove of the pulley when the vehicle is being depressed and the cable is slackened on the drum and the spring, 5, is reacting for taking up the slack; and it will be observed that the dimensional relation between the pulley and the drum, the two being equal in outside diameter,—and the spiral groove of the drum running out at the edge adjacent to the pulley, and the groove of the pulley being substantially as near the face of the pulley which is adjacent to the face of the drum as the normal distance between the coils of the spiral groove of the drum, facilitate this transfer of the cable from drum to pulley and pulley to drum in the back and forth oscillation of the pulley.

I claim:—

1. In a snubber, comprising a fixed friction member, a flexible connector wrapping the friction member, and a spring for retracting the flexible connector around the fixed member; a mounting device for securing the fixed friction member to the vehicle, consisting of a disk having a bolt aperture, and at one side an annular serrated area around said aperture, and having a radially

extending arm provided with a projection away from the serrated side of the disk; the fixed friction member having a central bolt hole and an annular serrated area corresponding to and adapted to co-operate with the annular serrated area of the disk, and a bolt engaging the fixed friction member at said bolt hole therein, and extending through the disk for clamping the disk between the vehicle frame and the fixed member.

2. In the construction defined in claim 1, foregoing, a casing enclosing the fixed friction member, the flexible connector thereon and the connector retracting spring, said casing having a peripheral aperture for emergence of the flexible connector, and being rotatably mounted about said fixed friction member, the latter having an axial stem for so mounting the casing; spring disk on the protruding end of said stem peripherally bearing on the casing, and a nut screwed into said stem for tensioning the disk against the casing for holding it yieldingly subject to rotation, for positioning the peripheral aperture in accordance with the direction of emergence of the flexible connector.

3. In a snubber, in combination with a fixed drum, a flexible connector wound upon the drum for friction thereabout; a spring coiled about the drum axis having its outer end connected with the flexible connector; the drum having a fixed stud axle, a sleeve on said stud axle to which the inner end of the coiled spring is secured; a spring disk connected for rotation with said sleeve, whereby the spring disk is adapted to serve as a handle for rotating the sleeve to tension the spring, and a nut on the stud axle for clamping the sleeve and disk to the stud axle against rotation thereabout.

4. In a snubber, in combination with a fixed friction drum having a spiral groove for seating a cable connector, a spring actuated pulley having substantially the same diameter as the drum and having a groove for winding the cable thereon, the groove of the drum emerging laterally with respect to the drum at the side adjacent the pulley, and the pulley groove being closely proximate to the side of the pulley adjacent the drum—the groove of the drum being sloped as to depth for a short distance back of the said lateral emergence so as to emerge with negligible depth, whereby the cable may pass over into the groove of the pulley without abrupt bending to climb onto the marginal wall of the pulley groove.

5. In a shock absorber adapted to be secured to a vehicle frame, comprising a strap for actuating said shock absorber, a bolt extending through said shock absorber and vehicle frame, a mounting device co-operating with said bolt for securing said shock absorber to said vehicle frame, said mounting

device consisting of a disk formed with a bolt hole, and at one side formed with an annular serrated face around said bolt hole, an integral radially extending arm having a projection away from said serrated side of the disk, a serrated face rigid with said shock absorber and co-operating with said serrated face of the mounting device, said serrated faces being rigidly secured together by said bolt.

6. In combination with a strap operated shock absorber adapted to be secured to a vehicle frame, a bolt extending through said shock absorber and frame, a mounting device co-operating with said bolt for securing said shock absorber to said frame consisting of a hub portion against one face of which a face of said shock absorber abuts, said hub being formed with a bolt hole and having a rigid radially extending arm having a projection away from said hub face, the abutting faces of the hub and shock absorber having interengaging portions affording means for rotatably adjusting said shock absorber upon said hub and being rigidly secured together by said bolt.

7. In a shock absorber in combination with a fixed drum, a flexible connector wound upon the drum for friction thereabout; a spring coiled about the drum axis having its outer end connected with a flexible connector, means mounted for rotation relatively to the fixed drum about the axis of the drum, the inner end of the spring being secured to said means, and means forming a permanent part of the structure and adapted for manually operating said rotatable spring securing means for tensioning the spring.

8. In a shock absorber in combination with a fixed drum, a flexible connector wound upon the drum for friction thereabout; a spring coiled about the drum axis having its outer end connected with the flexible connector, a fixed stud bolt at the center of the drum, a casing comprising a main member adapted to be mounted fixedly with respect to the vehicle, and a cover member for enclosing the spring and a drum; means extending from the fixed member out through the cover member for retaining the latter in relation to the former; a part to which the inner end of the spring is secured mounted rotatably on said bolt and extending thereon out through the cover; means applied to the protruding end of the bolt stopping said spring-engaging part longitudinally of the bolt, and means outside the cover and behind said stopping means on the end of the bolt constituting a permanent part of the structure engaged for rotation with said rotatable spring engaging part and manually operable for rotation of the same to tension the spring.

9. In the construction defined in claim 7,

foregoing, the means engaged with the spring, and hold the spring engaging member against reverse rotation by the reaction spring comprising spring fingers pressing upon the outer surface of the cover for holding the same to the main member of the casing, and serving for manual engagement for rotating said member to tension the

spring. In testimony whereof, I have hereunto set my hand at Chicago, Illinois, this 3rd day

of April, 1923.

LEONARD H. WHEELER.
